POURING SPOUT

Filed Sept. 14, 1928

UNITED STATES PATENT OFFICE

PORTR H. FLAUTT, OF BALTIMORE, MARYLAND, ASSIGNOR OF ONE-HALF TO FRANCIS C. YINGLING, OF BALTIMORE, MARYLAND

POURING SPOUT

Application filed September 14, 1928. Serial No. 306,039.

The present invention relates to an improved form of pouring spout for friction top cans.

One of the objects of the invention is to provide a pouring spout having frictional engaging means thereon to fit various size cans having different sized openings.

Another object of the present invention is to provide a pouring spout for friction top cans having a top which may be simultaneously opened with the lifting of the can preparatory to pouring the contents therefrom.

In the accompanying drawings I have illustrated a pouring spout for a friction top can embodying the various features of my invention in their preferred form.

Figure 1 is a side elevation of the invention as applied to a large size can showing the top of the pouring spout in open position in fine dotted lines.

Figure 2 is a plan view of the same.

Figure 3 is another side elevation similar to Figure 1, showing the invention as applied to a small size can.

Figure 4 is still another side elevation of the invention of pouring spout but taken at right angles, and from the left, of Figure 1, portions of the figure being broken away for purposes of illustration.

Referring to the drawings by numerals, the invention is shown as applied to a friction top can 1, the same having an opening 2 formed by a downwardly depending annular flange 3. This flange 3 is for the purpose of frictionally engaging the well known friction top for cans of this type. It is the purpose of the invention to take the place of this top, particularly for use with canned syrup. Preparatory to using a can of syrup upon the table at home the regular friction top may be removed and discarded completely, and in the place thereof the present invention substituted, by inserting same in the opening 2 of the can. The contents or syrup may then be poured from the can with all the convenience of a syrup pitcher, but without the inconvenience of having to transfer the syrup from one container to another.

The pouring spout invention consists of a top 4, an upwardly disposed annular flanged

portion 5, which may be termed the body 6, said annular flanged portion 5 forming an opening 7, through which the syrup or can contents may be poured. The top 4 may be pivotally engaged to the body 6, by means of the brackets 8 and ears 9 on the body 6 and the top extension or finger engaging means 10 respectively. These may be pivotally engaged by the pin 11, and the same may carry the coil spring 12 having an extension 14 therefrom for purposes of creating tension on the finger engaging member 10, to keep the top in closed position.

It will be noted that the finger engaging member 10 is downwardly disposed and approximately 90° away from the pouring lip in a horizontal plane. This position of the finger engaging member 10 to the pouring lip 15 enables the person pouring the contents from the can to more readily raise the top 4 with the fore finger of the same hand that is used to lift the can.

The lower portion of the pouring spout is formed into two step shaped annular flanges 17 and 18. These annular shaped flanges 17 and 18 each forms a circumferential frictional engaging surface 19 for a large size can such as a two pound can and the smaller frictional circumferential surface 20 for the smaller size can such as a one pound can, thus enabling the one pouring spout to fit cans having different sized openings formed by the flange 3. It may readily be seen that any number of different sized frictional circumferential surfaces such as 19 and 20 may be superimposed upon one another as shown for the purpose of frictionally engaging the can flange 3 that would be met with on various sized cans. Particular reference is made to Figures 1 and 3, which illustrate this feature. The pouring spout is shown as fixed to a two pound can in Figure 1, causing the flange 3 to engage the frictional engaging surface 19 of the step 17. Figure 3 shows the same pouring spout as applied to a smaller can such as a one pound can having a smaller opening in the top thereof, thus bringing into engagement with the flange 3 the frictional engaging surface 20 of the step portion 18.

I have thus described my invention specifically and in detail in order that its nature and operation may be fully understood; however, the specific terms herein are used descriptively rather than in their limiting sense, and the scope of the invention is defined in the claims.

What I claim and desire to secure by Letters Patent is:

- 10 1. A pouring spout for friction top cans having a plurality of frictional engaging surfaces of different perimeters, each of which is adapted to tightly engage the inner edge of a friction top can for the purpose of securing said pouring spout to said friction top can.
- 15 2. A pouring spout for friction top cans having a plurality of different sized annular can engaging surfaces of different perimeters, each of which is adapted to tightly engage the inner edge of a friction top can for the purpose of securing said pouring spout to said friction top can.
- 20 3. A pouring spout for friction top cans having a lid thereon, said lid being hingedly engaged thereto and having a downwardly disposed finger engaging member, positioned substantially at right angles to the pouring tip, whereby inwardly directed pressure on said finger engaging member opens said lid, a vertically extending portion on the lower portion of said pouring spout adapted to tightly engage the inner edge of a friction top can for the purpose of securing said pouring spout to said friction top can.
- 25 4. A pouring spout for a friction top can, the lower outside portion of said spout forming a plurality of vertically extending portions of different perimeters, each of which is adapted to tightly engage the inner edge of a friction top can.
- 30 5. A pouring spout for a friction top can, the lower outside portion of said spout forming a plurality of vertically extending portions of different perimeters, each of which is adapted to tightly engage the inner edge of a friction top can, shoulders on each of said vertically extending portions to limit the insertion of said spout into said can.
- 35 6. A pouring spout for a friction top can, a hinged lid thereon, an extension on said lid back of the hinge and disposed downwardly from said lid, whereby inwardly directed pressure on said extension opens said lid, a vertically extending portion on the lower portion of said spout adapted to tightly engage the inner edge of a friction top can.

Signed by me at Baltimore, Maryland, this 13th day of September, 1928.

PORTER H. FLAUTT.
